UNITED STATES PATENT OFFICE.

NORTON A. NEWDICK, OF COLUMBUS, OHIO, ASSIGNOR TO THE COLODER COMPANY, OF COLUMBUS, OHIO, A CORPORATION OF DELAWARE.

METHOD OF HANDLING SLATE.

Application filed September 6, 1923. Serial No. 661,303.

To all whom it may concern:

Be it known that I, NORTON A. NEWDICK, a citizen of the United States, residing in Columbus, in the county of Franklin, State 5 of Ohio, have invented certain new and useful Improvements in Methods of Handling Slate, of which the following is a specification.

This invention relates to an improved 10 method for facilitating the mining of coal in underground mines, and the general object of the invention is the provision of a system whereby the roof slate, commonly encountered in coal mines, may be economically 15 and rapidly removed from the region of a working face following the usual step of disrupting the coal vein to produce the desired free pile of gatherable coal.

In accordance with the present invention 20 there is provided a method for mining coal which consists in removing the slate from the coal pile in the same condition and size as it falls from the roof, or in other words, without preliminary reduction or breakage there- 25 of on the coal pile, so that the coal pile will contain but a minimum of shattered slate particles, and the slate removed to desired places of deposit conveniently and economically and with but a minimum of manual 30 labor, and with far greater rapidity and thoroughness than has been attained through and employment of any prior system of which I am aware.

In the accompanying drawing there has 35 been diagrammatically disclosed the various steps employed in practicing my improved method and also the apparatus used in connection therewith. In said drawing:

Figure 1 discloses a vertical sectional 40 view taken through the room of a coal mine, illustrating the manner of preparing the coal vein prior to the operation of blasting or shooting the vein to produce a gatherable pile of coal.

Figure 2 is a similar view disclosing the 45 coal vein following the blasting or shooting operation, showing the free pile of coal and the overhead unsupported stratum of draw slate.

Figure 3 is a vertical sectional view showing 50 the draw slate deposited on the top of the coal pile, after the slate has been broken loose from its natural state of adherence to the mine roof, and further illustrating a portable crane, used in carrying out the in-

vention, in the operation of dragging or drawing the slate down upon the mine floor at the base of the coal pile.

Figure 4 is a similar view showing the portable crane elevating or raising a slate 60 slab and, in dotted lines, in a position permitting the deposit of the slate at a desired place of discharge.

Most bituminous coal is found in level, 65 horizontally extending beds or veins of varying thickness, commonly ranging from four to ten feet, and in the extraction of this coal from its natural state it is the common practice to use the so-called room and pillar system of mining, which consists in 70 driving rooms or corridors thru the coal and then in attacking the blocks of coal, termed pillars, existing between the spaced rooms or corridors. As shown in the drawings, the numeral 1 designates the room of 75 a mine, the numeral 2 the coal vein, 3 represents the roof of the mine and the floor is designated by the numeral 4. In reducing the solid coal vein to a gatherable condition it is customary to blast down a portion thereof along the working face 5, and this is accomplished by producing one or more horizontally extending kerfs 6 in the face of the coal, which kerfs extend back 80 from the face 5 into the body of the coal a 85 distance varying from five to ten feet. Cutting machines of common construction are used in producing these kerfs. The latter may be situated either adjacent the floor 4, shown in Figure 1, or at any other desired 90 position in the thickness of the coal vein. In addition to the kerfs 6, the coal face is drilled to produce shot holes, in which is suitably placed and tamped a suitable charge 95 of an explosive 8 which, upon explosion or combustion, produces pressures or forces which disrupt the coal and reduce the same to the shattered mass or pile indicated at 100 9 in Figures 2 and 3. This mass of coal contains lumps of such size as to permit the loading of the coal into suitable cars or carriers, either by manual or machine operations. My system, however, is preferably 105 used in connection with mechanical loading machine and is especially fitted therefor.

The floor and the roof consist of solid, 110 substantial, homogeneous slate layers or strata which are not immediately impaired or influenced by the shooting of the coal. However, in most mines there exists imme-

diately above the coal vein and beneath the slate strata constituting the roof of the mine, a comparatively thin stratum of slate, commonly known as draw slate, and which does not possess the homogeneous qualities which characterize the slate constituting the roof and the floor. The draw slate varies in thickness but frequently averages between six and eighteen inches. Following the shooting of the pile this slate either falls on the top of the coal pile or insecurely clings to the roof of the mine, as shown in Figure 2, producing a dangerous overhanging roof condition which, if not removed, may cause serious injury to those engaged in the operation of loading the coal. Therefore, it is the practice, immediately following the shooting of the coal, to pry down from engagement with the roof such draw slate as may adhere to the roof, permitting the same to fall in slabs or lump-like pieces 10, indicated in Figure 3, which find lodgment upon the top of the coal pile.

As before stated, it has been the custom to remove these slate lumps or slabs by hand. This is a slow, laborious and tedious operation because of the labor involved materially effects the cost of mining coal. In this operation it has been customary, either by the use of sledge hammers or small charges of explosives, to reduce these slate lumps to relatively small dimensions while the same are deposited on the coal pile, thus making them more readily adaptable to be lifted manually and moved to desired points of deposit. However, by breaking the slate up in this manner the small fragments thereof become intermingled with the main body of coal, producing foreign substances in the coal which materially effect its quality and rating, and by expensive processes removed from the coal, before the latter is ready for commercial use.

To obviate this, the present invention consists in using slate machine 11, which is in the nature of a portable crane, as has been set forth and claimed in detail in my co-pending application filed May 22, 1922, Serial Number 562,803. The mechanical details of this machine may, for present purposes, be described as consisting of a portable body 12, adapted to travel over a trackway 13 provided in the room 1. Arising from the base 12 is a horizontally turning column 14, upon which is pivoted as at 15, the boom 16 of the crane. The outer end of the boom 16 is provided with a pulley or sheave 17 around which is trained a cable or chain 18, the said cable being guided over the top of the column 14 by the shoe 19, and its inner end is engaged with a drum or windlass 20, which is driven by a motor 21, the said windlass controlling the effective length of the cable. The boom 16 may be supported by means of a shelf 22 formed

with and projecting horizontally from the column 14. This construction permits the boom to be moved in a vertical plane about its pivot 15, and also to turn in a horizontal plane by rotating bodily with the column 14. 70

As shown in Figure 3, the outer end of the cable 18 has connected therewith a pair of tongs 23, which is arranged to grip the slate slabs 10 and draw the same downwardly from their position upon the coal pile to the floor 4 at the base of the pile, with the slabs in the same condition as they are when they fall from the roof of the mine. In other words, my method involves no preliminary reduction in size of the slate slabs before being removed from the coal pile, or more positively stated, the slate slabs are handled in bulk and in the same size and condition as when they fall from the mine roof. This is true even though the slabs 85 may weigh several tons each, although, of course, such an extreme weight is rather an unusual condition. Following the drawing of the slate slabs in their original size down to the base of the coal pile, the outer end of the cable 18 has connected therewith a plurality of hooks 24, preferably three in number and connected by chains 25, with an eye 26 provided upon the outer end of the cable 18. This grapple arrangement enables the slate slabs, regardless of their irregular contour, to be readily engaged with said cable and lifted or elevated as the inner end of the cable is wound about the drum 20. When the slate slabs have been lifted from the 100 floor, the machine 11 may be moved longitudinally upon the trackway any suitable distance, carrying the slate slabs with it and, as shown in Figure 4, these slabs may then be stacked or placed in neatly arranged piles 105 27 to each or either side of the room 1 and the trackway 13 therein, where the slate particles may be out of the way of rolling stock moving in and out of the room over the trackway 13 and to other positions remote from the pile 9. In certain mines it is the custom to remove the slate entirely from the mines, in which event the machine 11 may be used to position the slate slabs in the cars used in transporting the slate from place to place. This operation may be carried out with the slate slabs in their original shape and condition as when the same fell from the roof, without breakage or reduction in size of any kind. 110 115 120

What is claimed is:

1. The method of mining coal which consists in disrupting the natural coal vein along a working face, to produce the free pile of gatherable coal, in removing from the roof of the mine over said coal pile, the clinging stratum of draw slate which adheres to the mine roof following the disrupting of the coal vein, permitting said slate to drop down and deposit itself on the 125 130

coal pile in relatively large slabs or pieces, and in removing the slate from the coal pile in the same condition as it falls, without preliminary reduction or breakage there-
5 of on the coal pile.

2. The method of mining coal, which con-
sists in shooting or releasing the coal from
its natural state to create the desired free
pile of coal, releasing the overhead roof slate
10 in the region of the pile, causing the de-
posited slate slabs or pieces to ride over the
pile to a base position without preliminary
reduction or breakage thereof on the coal
pile, and in removing the slabs or pieces
15 bodily from said base position to a suitable
point of deposit.

3. The method of mining coal which con-
sists, in disrupting the natural coal vein
to produce a free pile of gatherable coal, in

removing from the roof of the mine over
said coal pile, the clinging stratum of draw
slate adhering to the mine roof following
the disrupting of the coal vein, and in re-
moving the slate from the coal pile in the
same condition as it falls.

4. The method of preparing coal for load-
ing, which consists in shooting or releasing
the coal from its natural state to create the
desired free pile of coal, releasing the over-
head roof slate in the region of the pile,
30 causing the deposited slate slabs or pieces
to ride over the pile to a base position, and
in removing the slate slabs or pieces from
said base position to a suitable point of de-
posit.

In testimony whereof, I have signed my
name to this specification.

NORTON A. NEWDICK.
